UNITED STATES PATENT OFFICE.

HEINRICH BOLTSHAUSER, OF ZURICH, SWITZERLAND.

TURBINE-DRIVEN LOCOMOTIVE.

Application filed May 25, 1925, Serial No. 32,652, and in Switzerland May 30, 1924.

The invention refers to a turbine driven locomotive having at least two driving turbines working in parallel. Locomotives of this type are especially suitable for developing large powers as with these locomotives in spite of large quantities of steam consumed the blades of the last stages of the turbines have not to be made of excessive length. If the turbines work on the driving axles through the interposition of toothed gearings the further advantage is obtained that also with large outputs of the turbines the width of the gear wheels does not get excessive, so that the wheels are not distorted when transmitting heavy loads, do not produce too much noise and are not subjected to a quick wear owing to excessive stresses.

The object of the present invention is to provide a locomotive of the above mentioned type comprising one or more groups of turbines of simple and compact design. This is of great importance with locomotives on which the available space is extremely limited.

To this end according to the present invention the turbines are arranged to the same side of the longitudinal centre plane of the locomotive and they have an exhaust branch common to both turbines. This arrangement presents the further advantages that leakage losses on connecting points as well as losses due to drop in pressure and the like are limited to a minimum amount. Where it is necessary to subdivide the condenser owing to its weight, the exhaust branch may be connected to a part of the condenser arranged in front of the turbines of the group as well as to one or more parts of said condenser arranged laterally of the locomotive boiler.

Constructional examples of the subject matter of the present invention are diagrammatically illustrated on the accompanying drawings, in which:

Fig. 1 shows a turbine driven locomotive provided with a condenser subdivided into three parts,

Fig. 2 shows in a plan-view, with the boiler removed, the turbine and the parts of the condenser of this locomotive and some parts of the drive.

Fig. 3 shows in a plan view corresponding to that shown in Fig. 2 a constructional example in which the condenser is arranged in front of the two turbines, and

Fig. 4 shows in a plan-view a further arrangement, in which one part of the condenser is arranged in front of the turbines and a second part of the condenser is situated to the side of the locomotive boiler.

Fig. 5 shows in an elevation view a turbine driven locomotive and a driving tender provided with driving turbines and with a recooling device for the cooling water of the condenser.

In the various figures, 1 and 2 denote two turbines the axes of which are parallel to each other and at right angles to the longitudinal axis of the locomotive. The turbines 1 and 2 are situated on the same side of the longitudinal centre plane of the locomotive. Each of the turbines contains a larger number of stages for the ahead running and a smaller number of stages for the astern running. 3 denotes the steam supply pipe.

Each of the two turbines 1 and 2 actuates a lay shaft 6 by the interposition of a toothed gearing 4 and 5 respectively comprising a gear wheel 15 common to both; the power transmission from the lay shaft 6 to the driving wheels 17 is effected in a known manner by means of a parallel crank gear 16. The turbines 1 and 2 are provided with an exhaust branch 7 common to both which is connected to a condenser part 8, arranged in front of the turbines on the front part of the locomotive as well as the two condenser parts 10, 11 arranged laterally of the locomotive boiler 9. The turbines 1 and 2 are arranged laterally of the common exhaust branch 7 and are preferably so dimensioned that each of them delivers approximately one half of the desired power of the locomotive and consumes therefore approximately one half of the total amount of steam.

Instead of subdividing the condenser into three parts the latter may be designed as a single body in the manner shown in Fig. 3, where it is designated by the reference numeral 12. In this embodiment the condenser is arranged in the front part of the locomotive before the turbines 1 and 2. The parts in this figure which correspond to those in the first constructional example are designated by similar reference numbers.

Fig. 4 illustrates an arrangement with a condenser consisting of two parts 13 and 14, of which part 13 is arranged in front of the turbines 1, 2 and part 14 is arranged laterally of the locomotive boiler 9. The exhaust

branch 7 common to the turbines 1 and 2 is connected to both parts 13 and 14 of the condenser, the turbines 1 and 2 situated to the same side of the longitudinal centre plane of the locomotive are also in this case arranged laterally of this branch 7. 3 denotes again the steam supply pipe and 4, 5 are gear wheels of the transmission gearing.

The manner in which the drive is effected

10 from the turbines 1 and 2 to the driving axles is immaterial to the essence of the present invention. For instance, the pinions 18, 19 of the first transmission ratio of the two turbines 1 and 2 may cooperate with a gear wheel 20 common to both pinions, instead of providing, as illustrated in Figs. 1 and 2 a common gear wheel 15 on the lay shaft 6 with which the pinions of the second transmission ratio cooperate.

15 20 Finally, it may be mentioned that in the manner illustrated in Fig. 5 several groups of turbines of the above described type may be used, for instance one group 1, 2 in the front on the locomotive and another group 21, 22 at the rear on the tender which is provided with a recooling device 24 for the cooling water of the condenser. In this case one group of turbines may, for instance, solely consist of ahead turbines and the other solely of astern turbines.

I claim:

1. A turbine driven locomotive comprising at least one set of two driving turbines arranged at the same side of the longitudinal central plane of the locomotive, the two turbines of each set working in parallel and transmitting power to a common driving gear, and an exhaust branch also common to both turbines.

2. A turbine driven locomotive comprising in combination, a locomotive boiler, at least two driving turbines arranged to the

same side of the longitudinal centre plane of the locomotive, an exhaust branch common to both turbines, and a condenser, one part of which being arranged in front of the turbines and another part being arranged laterally of said locomotive boiler, said common exhaust branch being connected to said parts of the condenser.

3. A turbine driven locomotive comprising in combination a locomotive boiler, at least two driving turbines arranged to the same side of the longitudinal centre plane of the locomotive, an exhaust branch common to both turbines, and a condenser consisting of three parts of which one part is arranged in front of the turbines and the other two parts are arranged on different sides of the locomotive boiler, said common exhaust branch being connected to all the parts of the condenser.

4. A turbine driven locomotive having a locomotive frame and a boiler thereon in combination with at least two driving turbines for the locomotive working in parallel and arranged at the same side of the locomotive frame and between the frame and boiler, and an exhaust branch common to both turbines.

5. A turbine driven locomotive having a locomotive frame and a boiler thereon in combination with at least two driving turbines for the locomotive working in parallel and arranged to the same side of the locomotive frame, an exhaust branch common to the turbines, and a sub-divided condenser connected to said exhaust branch, one of the condenser parts extending across the frame at the front thereof.

In testimony whereof I have signed my name to this specification.

HEINRICH BOLTSHAUSER.
